UNITED STATES PATENT OFFICE.

WALTER WILKINSON, OF PHILADELPHIA, PENNSYLVANIA.

PICKER STICK.

Application filed January 18, 1923. Serial No. 613,378.

To all whom it may concern:

Be it known that I, WALTER WILKINSON, a citizen of the United States, residing at Philadelphia, in the county of Philadelphia and State of Pennsylvania, have invented new and useful Improvements in a Picker Stick, of which the following is a specification.

My invention relates to new and useful 10 improvements in a picker stick, and has for its primary object to construct the major portion of such a stick of metal whereby the liability of breakage is greatly reduced and the life of the stick increased.

15 Another object of the invention is to improve the construction of picker sticks in general and more specifically to employ a short wooden section for contact with the picker, such wooden section being removable for the substitution of a new section and also reversible and invertible in order that different surfaces may be employed.

A further object of the invention is to provide an adjustable clamp to connect the connecting rod or sweep stick to the picker stick, such clamp being made of either cast 20 or sheet metal.

A still further object of the invention is to provide for adjustably connecting a check 25 strap to the picker stick.

With these ends in view, this invention consists in the details of construction and combination of elements hereinafter set forth and then specifically designated by the 30 claims.

In order that those skilled in the art to which this invention appertains, may understand how to make and use the same, I will describe its construction in detail, referring 35 by numerals to the accompanying drawings forming a part of this application, in which:—

Fig. 1, is a side elevation of a picker stick embodying my improvements.

40 Fig. 2, is a similar view at right angles to Fig. 1.

Fig. 3, is a longitudinal sectional view of Fig. 2.

Fig. 4, is an enlarged end view of the 45 picker stick and with the clamp removed.

Fig. 5, is an enlarged sectional plan view of one form of clamp.

Fig. 6, is an enlarged plan view of another form of clamp.

50 Fig. 7, is an enlarged fragmentary side elevation of the picker stick illustrating one

method of attaching the check strap thereto. Fig. 8, is a similar view at right angles to Fig. 7 with a portion of the body broken away and shown in section. 60

In carrying out my invention as here embodied, 2 represents the metal body of the picker stick, the central major portion 3 of which is circular in cross section while at each end are formed the sockets 4 and 5 rectangular in section and preferably of oblong shape, as plainly shown in Fig. 4.

The socket 4 is adapted to receive either end of the short wooden section 6 having a plurality of equi-distant holes 7, two of 70 which are adapted to lie within the socket 4 when the wooden section 6 is in place and receive the screws 8 passing through one of the walls of said socket thereby preventing the accidental displacement of the wooden section; and to prevent said wooden section from being driven too far into the metal body, a stop element 9 preferably on the form of a rivet is mounted in the metal body just below the socket. 75

As one surface of the exposed end of the short wooden section 6 becomes worn, due to contact with the picker, said wooden section may be either reversed or inverted until all four surfaces have been utilized. The 80 surfaces referred to are the front and rear faces between each pair of adjacent holes 7.

In two walls of the socket 5 are formed the aligned holes 10 with which registers a hole 11 in the wooden filler 12 located within the socket 5, said holes 10 and 11 receiving the stud which pivotally mounts the picker stick on the loom, and said filler as well as providing a long bearing surface on the stud acts as a stiffener to prevent the collapse 90 of the socket 5, and the lower edge of said filler serves as a bearing surface for the pull strap 14.

Other aligned holes 13 are provided in the other walls of the socket 5 and with 100 these registers another hole 14 in the filler 12, these last named holes being at right angles to the holes 10 and 11 and are adapted to receive a suitable fastening means such as a bolt for attaching a retracting spring and 105 the strap of the picker stick.

Adjacent the upper end of the tubular portion of the metal body is formed a button hole slot 15 for the reception of a bolt 40, the head of which is passed through the enlarged aperture at the end of the slot and then drawn against the inner surface of the 110

metal body walls by the nut 41 having threaded engagement with the bolt on the outside of the picker stick body. Next the check strap 42 can be passed over the outer 5 end of the bolt 40 and then another nut 43 threaded onto the bolt to hold the strap in place and as will be obvious by loosening the nuts and moving the bolt lengthwise of the slot 15 within the limits of the restricted portion thereof for the adjustment 10 of said strap on the picker stick.

On the tubular portion of the metal body is also adjustably mounted a clamp 16 for connection of a sweep stick or connecting 15 rod and may be formed from either cast or sheet metal, as shown in Figs. 5 and 6, the sheet metal clamp being designated by the numeral 16 and the cast metal one by the numeral 16'.

20 The sheet metal clamp is bent or shaped to form the strap 17 having adjacent spaced ears 18 through which passes a bolt 19 having a nut 20 threaded thereon whereby the strap may be firmly clamped about the metal 25 body of the picker stick in order to prevent any movement of the clamp on the picker stick a screw 21 is threaded through the strap and impinges on the picker stick. The strap is also provided with a lug 22 within 30 which the head of the screw 23 sets and this screw has a nut 24 thereon for connection with the sweep stick or its equivalent.

The cast metal clamp shown in Fig. 5 consists of two sections 25 and 26 each 35 having a semi-circular portion 27 for engagement with the tubular portion of the metal body and outwardly ears 28. One of these ears has a fulcrum lug 29 at its extreme outer end to bear against the complementary ear whereby the semi-circular 40 sections may be drawn together by means of a bolt 30 on which is mounted a nut 31. The coacting ends of the semi-circular portions 27 each have a notch 32 to receive the head 33 of a bolt 34 passing through a lug 35 carried by one of the sections and this 45 bolt has a nut 36 screwed thereon for fastening the sweep stick or connecting rod.

The ordinary wooden picker stick requires 50 a number of holes intermediate its length for the adjustment of the sweep stick or lug strap thereby greatly weakening the stick at these points and because of this weakened condition the picker stick often 55 breaks in half and in addition will often split from the end having the stud hole therein and sometimes even splits from the

upper end due to the wear caused by constant contact with the shuttle. When the picker stick is damaged in any one of these 60 places it requires that such stick be removed and replaced by a new one.

The construction of the picker stick in the manner shown and described above overcomes these disadvantages as the metallic 65 body will be of sufficient strength to be practically unbreakable and should the short wooden section become damaged another short section may be substituted therefor without the use of skilled labor and where 70 such damage is only undue wear to one of the surfaces of the wooden section it may be either reversed or inverted.

Of course I do not wish to be limited to the exact details of construction as herein 75 shown as these may be varied within the limits of the appended claims without departing from the spirit of my invention.

Having thus fully described my invention, 80 what I claim as new and useful is:—

1. A picker stick comprising in combination, a metal body having a socket at each end and provided with a button hole slot, said slot adapted to receive suitable fastening means for connecting a check strap 85 to the stick, a wooden filler in the socket at one end, said filler and the socket on which it is mounted having a hole therethrough to receive a stud, a wooden section reversibly and invertibly mounted in the other socket means to limit the inward movement 90 of said wooden section, means to prevent the accidental displacement of said wooden section and a clamp adjustably mounted upon a metallic body, said clamp adapted to 95 connect the sweep stick to the picker stick.

2. As an article of manufacture, a metallic picker stick body comprising a tubular intermediate section, a socket at each end of rectangular form in cross section, one of said sockets adapted to receive a wooden 100 filler to strengthen such end of the body and provide an extended bearing surface for a stud, another socket adapted to receive a reversible and invertible wooden section, 105 said body having a button hole slot between the sockets for the reception of fastening means to adjustably connect a check strap thereto, and means at the inner or lower end of the last named socket to limit the inward 110 movement of the wooden section.

In testimony whereof, I have hereunto affixed my signature.

WALTER WILKINSON.
